UNITED STATES PATENT OFFICE.

HAROLD BINNEY, OF NEW YORK, N. Y., ASSIGNOR TO NEALON COMPANY, A CORPORATION OF NEW YORK.

HOSE-SUPPORTER CLASP.

No. 853,758.

Specification of Letters Patent.

Patented May 14, 1907.

Application filed January 3, 1905. Serial No. 239,377.

To all whom it may concern:

Be it known that I, HAROLD BINNEY, a citizen of the United States, and a resident of No. 10 Lexington avenue, in the borough of Manhattan, city, county, and State of New York, have invented certain new and useful Improvements in Hose-Supporter Clasps, of which the following is a specification.

This invention relates to garment supporter clasps comprising a loop and a button, the shank of which is embraced in the loop; an edge portion of the garment, as the hem of a stocking or sock, being interposed therebetween and held thereby.

15 It particularly relates to clasps having a relatively rigid loop member commonly made of metal, either in sheet or wire form, and a button secured to or forming part of a flexible back, which back is flexed to insert the button into the loop and tends to regain its normal shape when permitted.

It consists in so relating the shank of the button to the back that the latter shall not interfere with the easy insertion of the button in the loop; in providing a back specially flexible in the desired direction, and in such other novel features as are shown in the drawings or will appear in the detailed description.

30 In the drawings, Figure 1 is a front elevation of a supporter clasp embodying my invention. Fig. 2 is a vertical section of the same showing the insertion thereinto of a stocking or article to be supported. Figs. 3, 35 5 and 7 are side elevations of modified forms of a portion of my device. Figs. 4 and 6 are front elevations of the parts shown in Figs. 3 and 5 respectively.

1 designates a loop, which as shown, has 40 the well known pear-shaped slot 11, the lower end 12 of which receives the rearwardly projecting shank 22 of a button head 21 attached to, or in the present instance integral with, the back 2. I ordinarily prefer to mold the back 2 and the button from rubber compound, though it is evident that the material or mode of union of these is immaterial to my present invention. Where, as shown in the drawings, the upper end of the flexible back 50 is clamped as at 23 to the loop 1, its flexible portion between the clamp and the button is rather short. It is therefore necessary in introducing the button and the stocking hem 3

engaged thereover into the upper broadened portion 13 of the slot 11 to bend the back 2 to approximately the shape shown in Fig. 2 of the drawings. In doing this with the devices as heretofore made, *i. e.*, those in which the back 2 extended downwardly approximately as far as the lower edge of the button head 60 21, and beyond the shank, I have found the lower edge of the back strikes against the side of the loop 1 so as to materially interfere with the easy manipulation of the clasp. By constructing the parts as shown so that no portion of the back 2 extends substantially below the shank 22 of the button head 21, or in other words, by attaching the shank at the extreme lower end of the back, this interference is eliminated and the button head 70 may be readily inserted, see Fig. 2 of the drawings, the shoulders 25 acting as a stop to prevent the back going through the loop.

By forming the back 2 with the transverse corrugations 24 shown, I considerably increase its longitudinal flexibility as well as its transverse rigidity without altering its strength.

I have shown the back 2 as reinforced by a backing of cloth or like material 26. It is 80 obvious that this forms no part of the present invention and it is well-known that flexible rubber backs of this general class may be made either with or without such backings.

It is evident that the button head 21 may, 85 instead of the usual axially disposed shank, have the shank eccentric of the button head, being either located at its lower edge as in Figs. 3 and 4, at the upper part of its rear face as in Fig. 7, or it may occupy the entire 90 vertical diameter of the back of the button head, as shown, in Figs. 5 and 6. In any case, the back 2 is so formed as to extend approximately only to the lower side of the shank 22 and to widen out behind the button 95 so as to prevent the lower end of the back being drawn into or through the portion 12 of the slot 11 by reason of the tension of the supported garment. The transverse collapsing of the back, by which this would be 100 permitted, is strongly resisted, as above indicated, by the corrugations 24.

In a co-pending application filed January 3rd, 1905, which has received Serial No. 239,378, I have shown and claimed a button 105 head having its shank or attaching portion

eccentrically located on its rear face and below its axial line. It is obvious that I do not herein broadly claim such a construction.

I have filed on even date herewith two 5 companion applications, numbered 239,378 and 239,379 respectively. In both of these is shown a button head having its shank eccentrically secured to its rear face, and in both the back plate is shown transversely 10 corrugated. It is obvious that I do not herein claim anything specifically claimed in either of these applications.

It is evident that other modifications, either of material or form other than those 15 shown may be made without departing from the spirit of my invention.

Having thus described my invention, what I claim and desire to secure by Letters Patent, is:

20 1. A garment supporter clasp comprising a loop, a button having a shank attached to its rear face, and a flexible back to which said button shank is connected, the lower end of said back extending downward only to the lower side of the button shank and being substantially wider than said shank.

25 2. A garment supporter clasp comprising a loop and an integral button and flexible

back, said button comprising a head and a shank attached to the rear face of said head 30 and connecting said head with said back at the extreme lower end of the latter.

3. A garment supporter clasp comprising a loop and an integral button and flexible back, the shank of said button being connected with said back at the extreme lower end of the latter, said lower end of the back being substantially wider than said shank. 35

4. A garment supporter clasp comprising a loop, a button, and a back to which said 40 button is attached, said back having transverse lines of decreased resistance to flexion.

5. A garment supporter clasp comprising a loop, a button, and a transversely corrugated 45 flexible back, to which said button is connected.

6. A garment supporter clasp comprising a loop, and an integral button and transversely corrugated flexible back.

In testimony whereof I have signed this 50 specification in the presence of two subscribing witnesses.

HAROLD BINNEY.
